UNITED STATES PATENT OFFICE.

WILLIE B. WHITE, OF CLEVELAND, OHIO.

DESIGN FOR A SPEED-WAGON BODY.

SPECIFICATION forming part of Design No. 30,119, dated January 31, 1899.

Application filed November 13, 1897. Serial No. 658,500. Term of patent 7 years.

To all whom it may concern:

Be it known that I, WILLIE B. WHITE, a citizen of the United States, residing at Cleveland, in the county of Cuyahoga and State of Ohio, have invented and produced a new and original Design for Speed-Wagon Bodies, of which the following is a specification, reference being had to the accompanying drawings, forming a part thereof.

10 In the accompanying drawings, Figure 1 is a plan view of a wagon-body embodying my new design. Fig. 2 is a side elevation thereof.

As shown in the drawings, the leading and material feature of my design is comprised in 15 the shape or contour of the wagon-body A, on

which is a seat B, the said body being open across its top and fashioned with plain straight sides 2 2 and converging ends 3 3, which are in parallel vertical planes to the sides 2 2 and are divided by an edge 4 on the median line 20 of the body.

What I claim is—

The design for a speed-wagon body, substantially as described.

Witness my hand to the foregoing specification this 7th day of October, 1897.

WILLIE B. WHITE.

Witnesses:

H. T. FISHER,
R. B. MOSER.
